HEAT-EXCHANGE UNIT FOR WRAPPING MACHINES

William Stoneman, Jr., Kansas City, Mo., assignor of one-half to Merlin A. Sticelber, Kansas City, Mo.

Application September 7, 1935, Serial No. 39,579

14 Claims. (Cl. 62—126)

This invention relates to package wrapping and sealing machines and particularly the heat-exchange unit thereof which is employed to congeal the hot seals of the package as it passes through the machine, and the primary object of this invention is the provision in such a unit of refinements of construction which will render the same more efficient, durable and generally desirable because of the advantages gained from its use.

One of the objects of the invention is to provide a heat-exchange unit for wrapping machines which has as a part thereof, a wall comprising a number of substantially straight, superimposed conduits for a refrigerant, disposed in such a way as to present and form a relatively smooth planar wall along which the packages are passed and through which heat units are passed from hot seal to refrigerant, whereby to quickly and positively congeal the seal.

Minor objects of the invention constitute important aims thereof and a large number of them will appear during the course of the following specification, referring to the accompanying drawing, wherein:

Figure 1 is a top plan view of an heat-exchange unit for wrapping machines embodying this invention.

Fig. 2 is a vertical cross section through the same.

Fig. 3 is a longitudinal, vertical, condensed, sectional view taken through the plurality of conduits of one of the side members and on line III—III of Fig. 2.

Fig. 4 is a perspective view of the plurality of conduits entirely removed from the remaining elements of the unit.

Fig. 5 is a perspective, fragmentary view of one end of one of the unit members illustrating the manner of attaching the plurality of conduits to the boxing, and,

Fig. 6 is a perspective view of one of the plugs for the conduit.

The manner of adjustably supporting the two opposed side members 8 and the base member 10 and the way of supplying a suitable refrigerant to the conduits of these members is well known in the art. The passageway 12 which is formed for the packages between side members 8 and base member 10 may be altered with respect to its width between side members 8 by merely moving said members toward and from each other.

The structure embodying the preferred form of this invention is designed to dispose the heat unit absorbing refrigerant as close to the hot seal as

possible. It is further desired to have the refrigerant spread over the entire area of the contacting walls so that no voids along the contacting wall of members 8 and 10 will be presented to cause incomplete congealing and therefore a faulty seal. To this end, each of the members 8 of the selected embodiment of the invention illustrated comprises a plurality of conduits 14 that are rectangular in cross section and which have their ends closed by a plug 16 of special design.

Conduits 14 should be substantially straight from end to end and one face of each of the plurality of conduits 14 lies in a plane common with a face of the remaining conduits. The hollow wall thus formed by the plurality of conduits presents a substantially smooth surface 18, against which the seals of the package (not here shown) may be pressed and frictionally forced along as it traverses passageway 12.

Proximal conduits have their adjacent sides in abutting relation as illustrated in Figs. 2 and 3 and couplings are provided to interconnect the conduits 14 so that a serpentine path for the refrigerant is formed by conduits 14 and couplings 20. Connections to the coupled plurality of conduits 14 such as illustrated at 22 and 24 are provided for the purpose of introducing and removing the refrigerant. Each member 8 includes a boxing 26 that may be made of wood or metal and which has a filling of cork or other heat insulating material 28 therein to encase couplings 20 and which lies against the backs of the plurality of conduits 14 to the end that the action of the refrigerant is through the outer walls of the conduits which are in contact with package in passageway 12.

Base member 10 is constructed generally the same as side members 8 in that it has a plurality of superimposed edge-to-edge conduits 30 that are substantially rectangular in cross section and 40 interconnected by couplings 32 so that a continuous serpentine path for the refrigerant is created from intake connection 34 to outlet connection 36. One of the flat faces of each conduit 30 is in a common horizontal plane with the flat faces of 45 the remaining conduits, thereby to create a floor for the passageway.

A boxing 38 of wood or metal has a filling 40 of suitable insulated material so as to confine, as far as possible, the action of the refrigerant 50 to the opposite sides of conduits 30.

The longitudinal abutting edges of conduits 14 and 30 are not interconnected other than by mere frictional engagement and the plurality of conduits 14 on each side member 8 are secured 55

to boxing 26 by a plate 40 which is rigidly af-
fixed by screws or otherwise 42 to boxing 26 and
which is soldered to the ends of conduits 14 in
such a manner as to leave a layer of solder be-
5 tween the face of plate 40 and the ends of con-
duits 14. This solder is relatively pliable and
plate 40 is flexible enough to permit expansion
and contraction of conduits 14 while they are
in place and without injury thereto. Plugs 16
10 are secured inwardly from the ends of conduits
14 and plate 40 is provided with a series of holes
44 through which may be poured ordinary soft
solder for the purpose of filling the interstices
15 between plug 16 and plate 40 to further present
the desired cushioning aforementioned. Cou-
plings 20 secure together conduits 14 at points
spaced inwardly from the ends thereof and when
the conduits 14 lengthen and shorten by ex-
20 pansion and contraction respectively, the structure
just set down will be effective in preventing self-
destruction to the members.

Conduits 30 or base member 10 may be simi-
larly attached to boxing 38 and the conduits 30
25 plugged and connected in a specific manner as
described with respect to conduits 14.

An advantageous way of casting plugs 16 is
shown in Fig. 6 and since these plugs must be
secured in place by welding or silver soldering,
boss 46 serves to absorb and cause an even dis-
30 tribution of heat from the flame of the welding
torch as assembly takes place. The surfaces of all
conduits 14 and 30 which contact the package
should be smooth and the refrigerant supplied
to said conduits should be of sufficiently low tem-
35 perature to quickly absorb heat units from the
hot seal of the packages and in most instances
the refrigerant should be of such a temperature
as to create and maintain a thin layer of frost or
ice on the surfaces being engaged by the hot seals.
40 The temperature that is sufficiently low to
quickly absorb the heat units from the hot seals
of the package is appreciably below the freezing
point of water and therefore the refrigerant em-
ployed could not be ordinary circulating water,
45 especially in view of the length of the unit which
is appreciably shorter than those now employed
in wrapping machines to attain the same end.

Only the preferred embodiment of the invention
50 has been illustrated and described and it is
understood that many modifications with respect
to specific form might be made by one skilled in
the art without departing from the spirit of the
invention or scope of the appended claims.

Having thus described the invention, what is
55 claimed as new and desired to be secured by Letters Patent is:

1. In a package wrapping machine of the kind
described, a heat-exchange unit for congealing
the hot seals of the packages comprising a plu-
60 rality of straight conduits interconnected to form
a wall and to have a refrigerant of sufficiently low
temperature circulated therethrough to quickly
absorb heat units from the hot seals of the pack-
ages as they contact the said wall, each of said
65 conduits having a planar side, the planar sides of
all of the conduits forming said wall being in a
common plane whereby to present a substantially
smooth surface to contact the seals of the pack-
ages.

70 2. In a package wrapping machine of the kind
described, a heat-exchange unit for congealing
the hot seals of the packages comprising a plu-
rality of straight conduits interconnected to form
a wall and to have a refrigerant of sufficiently low
75 temperature circulated therethrough to quickly

absorb heat units from the hot seals of the pack-
ages as they contact the said wall, proximal con-
duits of said plurality of conduits having their
adjacent longitudinal sides in abutting relation.

3. In a package wrapping machine of the kind 5
described, a heat-exchange unit for congealing
the hot seals of the packages comprising a plu-
rality of straight conduits interconnected to form
a wall and to have a refrigerant of sufficiently 10
low temperature circulated therethrough to quickly
absorb heat units from the hot seals of the
packages as they contact the said wall, each
conduit of the said plurality of conduits having a
planar side, the planar sides of the adjacent 15
conduits being in abutting relation. 15

4. In a package wrapping machine of the kind
described, a heat-exchange unit for congealing
the hot seals of the packages comprising a plu-
rality of straight conduits interconnected to form
a wall and to have a refrigerant of sufficiently 20
low temperature circulated therethrough to quickly
absorb heat units from the hot seals of the
packages as they contact the said wall, each con-
duit of said plurality of conduits having at least
two planar longitudinal sides, proximal conduits 25
having their adjacent planar sides in abutting
relation and the other planar sides thereof dis-
posed in a common plane for the purpose specified.

5. In a heat-exchange unit of the character
described, a plurality of conduits, each rectangular 30
in cross section and all having one side thereof
in a common plane to present a smooth surface;
and insulation overlying the other sides of all of
said conduits.

6. In a heat-exchange unit of the character 35
described, a plurality of closed-end, straight con-
duits, each rectangular in cross section and all
having one side thereof in a common plane; in-
sulation overlying the other sides of all of said
conduits; and laterally projecting couplings join- 40
ing adjacent conduits at points spaced inwardly
from the ends thereof said couplings being em-
bedded in said insulation.

7. In a heat-exchange unit of the character de-
scribed, a plurality of closed-end, straight con- 45
duits, each rectangular in cross section and all
having one side thereof in a common plane, prox-
imal conduits having their adjacent edges in abut-
ting relation; a boxing covering the other sides
of said conduits; a filling of insulating material 50
in said boxing and couplings joining adjacent
conduits at points spaced inwardly from the ends
thereof projecting into said boxing.

8. In a heat-exchange unit of the character de-
scribed, a plurality of straight conduits, each 55
rectangular in cross section and all having one
side in a common plane; couplings joining the
conduits at points spaced inwardly from the ends
thereof to create a serpentine path for the pas-
sage of a refrigerant; and a plug for each end 60
respectively of said conduits.

9. In a heat-exchange unit of the character
described, a plurality of straight conduits, each
rectangular in cross section and all having one 65
side in a common plane; couplings joining the
conduits to create a serpentine path for the pas-
sage of a refrigerant; and a plug for each end
respectively of said conduits, each of said plugs
being spaced inwardly from the end of the con-
duit which it closes. 70

10. In a heat-exchange unit of the character
described, a plurality of straight conduits, all
having one side in a common plane; couplings 75
joining the conduits to create therewith a ser-
pentine path for the passage of a refrigerant; a

support for the conduits; and a flexible bracket joining together the conduits and support adapted to permit expansion and contraction of the conduits with respect to the support.

5 11. In a heat-exchange unit of the character described, a plurality of conduits all having one side in a common plane; couplings joining the conduits to create therewith a serpentine path for the passage of a refrigerant; a boxing along 10 the other sides of said conduits; and a flexible plate joining together all of said conduits at each end respectively of the plurality thereof and secured to said boxing whereby to permit expansion and contraction of the conduits with respect to the boxing.

15 12. In a heat-exchange unit of the character described, a plurality of conduits all having one side in a common plane; couplings joining the conduits at points spaced inwardly from the ends thereof to create therewith a serpentine path for the passage of a refrigerant; a plug closing each 20 end of the conduits; a boxing along the other sides of said conduits; a flexible plate joining together all of said conduits at each end respectively of the plurality thereof and secured to said boxing; and a filling of pliable material between and serving to join together said conduits and plate.

25 13. In a heat-exchange unit of the character described, a plurality of conduits all having one side in a common plane; couplings joining the

conduits at points spaced inwardly from the ends thereof to create therewith a serpentine path for the passage of a refrigerant; a plug closing each 5 end of the conduits; a boxing along the other sides of said conduits; a flexible plate joining 10 together all of said conduits at each end respectively of the plurality thereof and secured to said boxing; and a filling of pliable material between and serving to join together said conduits and plate, said plugs being spaced inwardly from the 10 ends of the conduits to provide a space for the reception of said pliable material.

14. In a heat-exchange unit of the character described, a plurality of conduits all having one side in a common plane; couplings joining the 15 conduits at points spaced inwardly from the ends thereof to create therewith a serpentine path for the passage of a refrigerant; a plug closing each end of the conduits; a boxing along the other sides of said conduits; a flexible plate joining together all of said conduits at each end respectively of the plurality thereof and secured to said boxing; and a filling of pliable material between 20 and serving to join together said conduits and plate, said plugs being spaced inwardly from the 25 ends of the conduits to provide a space for the reception of said pliable material, said boxing having a filling of heat insulating material therein encasing said couplings and in contact with the sides of said conduit.

30 WILLIAM STONEMAN, JR.
